(57) CLAIM

The ornamental design for a claw-shaped baking form, as shown and described.

DESCRIPTION

FIG. 1 is a top view of a first embodiment of my baking form, which is the same as the bottom view thereof;

FIG. 2 is a left side view thereof, which is the same as the right side view thereof;

FIG. 3 is a front view thereof;

FIG. 4 is a rear view thereof; and,

FIG. 5 is a left side view of a second embodiment of my baking form, which is identical to the first embodiment except that it is thicker.
